(57) **CLAIM**

The ornamental design for a display screen or portion thereof with transitional graphical user interface, as shown and described.

DESCRIPTION

FIG. 1 is a front view of a display screen or portion thereof with transitional graphical user interface showing a first image of our new design.

FIG. 2 is a front view showing a second image thereof.

FIG. 3 is a front view showing a third image thereof.

FIG. 4 is a front view showing a fourth image thereof; and, FIG. 5 is a front view showing a fifth image thereof.

The dot-dash broken lines in the drawings show a display screen or portion thereof, and form no part of the claimed design.

The appearance of the transitional image sequentially transitions between the views of FIGS. 1-5. The process or period in which an image transitions to another forms no part of the claimed design.

1 Claim, 1 Drawing Sheet
